SWITCH ACTUATING DEVICE

Stephen Crum, Minneapolis, Minn., assignor to
 Minneapolis-Honeywell Regulator Company,
 Minneapolis, Minn., a corporation of Delaware

Application October 13, 1939, Serial No. 299,317

6 Claims. (Cl. 200—155)

This invention relates generally to actuating devices for switches and is more particularly directed to a mechanism for adjusting the differential of operation of a switch which is controlled in accordance with the variations in a variable condition.

It is old and well known in the prior art to obtain a differential adjustment on an automatic switch by means of a lost motion connection between a condition responsive device and the switch actuated thereby, said lost motion connection comprising a pin extending within a tapered slot. The pin in most cases is adjustably mounted directly on one of the parts which are moved by means of the condition responsive device for actuating the switch. In order to adjust the operating differential of the switch in a device of this type it is necessary to manually vary the position of the pin on the movable member upon which it is mounted. If this is done carelessly, or by some unskilled hand, it is quite possible that the moving parts may be damaged or too great a strain placed on the condition responsive device so that it is permanently deformed or the calibration upset. It is therefore seen that an adjustment of the differential is a delicate one requiring skill and care in prior art devices of the pin and slot type.

It is a primary object of the present invention to provide an automatic switching device having a pin and slot type of differential adjustment wherein the member for adjusting the differential is mounted on a fixed support so that no damage can be done the moving parts of the device by adjusting the operating differential, even though this adjustment be made carelessly by one not skilled in the automatic switching art.

Another object of the invention is to rotate a member having a tapered slot in response to variations in a variable condition, drive thereby a switch actuating member having a pin inserted in said slot, and vary the operating differential of said switch actuating member by bodily moving said switch actuating member and pin with respect to said tapered slot.

Still another object is to shape one edge of the slot so that the condition value at which the switch is actuated in one direction will remain the same regardless of the differential adjustment.

These and other objects will become apparent as the following specification is read in the light of the accompanying drawing, in which

Figure 1 is a front elevation of the switch actuating mechanism,

Figure 2 is a rear view of part of the mechanism shown in Figure 1, and

Figure 3 is a section taken along line 3—3 of Figure 2.

5 Referring now to Figure 1 of the drawing a base 11 is used to support the switch actuating mechanism and also to support a condition responsive device which may extend rearwardly of the base. This condition responsive device 10 may well take the form of a coiled bimetallic thermostat and may be mounted on the base 11 in the same manner as shown in my copending application Serial No. 299,316, filed October 13, 1939. The bimetallic element may be rotatably 15 adjusted by means of the adjusting arm 12 as shown in the aforementioned application and on variations in temperature may rotate the operating rod 13 shown in Figure 3.

A plate 14 is rigidly connected to the base 11 20 by means of the posts 15 and screws 16. A differential adjusting lever 17 is pivotally mounted at one end to the plate 14 as shown at 18. The spring element 19 is mounted concentrically with the lever 17 and offers a certain amount of 25 frictional resistance to the rotation of the lever 17 so that this lever will always remain in its adjusted position. The lever 17 is provided with a forwardly extending finger 20 which cooperates with a scale 21 on the plate 14 to indicate the 30 relative adjustment of this lever. The plate 14 is provided with a pair of shoulders 22 and 23 which limit the amount of movement which can be given the lever 17.

A shaft 25 is pivotally mounted through an 35 intermediate portion of the lever 17 by means of a sleeve 24 rigidly carried by lever 17 and a switch carrying member 26 is rigidly connected to the shaft 25 at the front of the plate 14. The member 26 carries a mercury switch clip 27 which in 40 turn supports the mercury switch 28. The lower end of the clip 27 is bifurcated as shown at 29 and between the bifurcations an eccentric screw 30 is rotatably mounted in the switch carrying member 26. Rotation of this screw 30 will 45 rotate the switch clip 27 about the shaft 25 to provide a calibrating adjustment whereby the switch may be properly aligned on the carrier 26. Rigidly mounted on the other end of the shaft 25 at the rear of the plate 14 is a crank arm 32 having a rearwardly extending projection 33. As the switch carrier 26 and crank arm 32 are both rigidly connected to the shaft 25 50 any rotation of the crank arm 32 will be transmitted to the carrier 26 to rotate the mercury switch 28.

The end of the operating rod 13 carries a hub 35 which may be held in any rotative position about the operating rod 13 by means of the set screw 36. The hub 35 rigidly carries an operating arm 37 which is provided with a tapered slot 38 through which the projection 33 on the crank arm 32 extends. It will therefore be seen that as the operating rod 13 is rotated in response to temperature variations by the bimetallic thermostat that it will rotate the crank 10 arm 32 and hence operate the mercury switch 28.

Assuming that the temperature is at a relatively low value and the switch has been actuated to closed position as shown in Figures 1 and 2 of the drawing and the temperature to which the 15 bimetallic element responds begins to increase the operating rod 13 will begin to rotate in a clockwise direction as seen in Figure 2. With the lever 17 adjusted to an intermediate position as shown, the projection 33 on the crank arm 32 will be in an intermediate position with respect to the length of the tapered slot 38. The tendency of the mercury switch 28 is to remain in the position to which it has been actuated and therefore as the operating rod 13 starts to rotate in a 20 clockwise direction in Figure 2 it will first move the operating arm 37 until the side 40 of the slot 38 engages the projection 33 on the crank arm 32. A further rotation of the operating rod 13 in the same direction will then cause a rotation of the crank arm 32 in a clockwise direction and the mercury switch 28 will be moved to open circuit position. As the temperature at the bimetallic 25 thermostat begins to decrease as a result of opening the switch 28 the operating rod 13 will begin to rotate in a counter-clockwise direction and the first movement of the operating arm 37 will first separate the side 40 from the slot 38 from engagement with projection 33 and cause the side 41 of this slot to engage the projection 33 and actuate the mercury switch to closed circuit 30 position again. It will be understood that while the lost motion provided by the slot 38 and projection 33 is being taken up the mercury switch 35 remains substantially stationary.

In order to adjust the extent of this lost motion and hence the operating differential of this switch the lever 17 is rotated about the shaft 18. If it is desired to increase the differential, the lever 17 is rotated in a clockwise direction as 40 seen in Figure 2. This movement will raise the shaft 25 which carries the mercury switch 28 and the crank arm 32 with its projection 33. The projection 33 will then be located in a wider part of the tapered slot 38 and hence the amount of 45 lost motion will then be greater. If it is desired to decrease the differential the lever 17 is rotated downwardly which will bring the projection 33 to the narrow part of the slot 38 and hence decrease the amount of the lost motion.

It is desired in this device that the temperature value at which the switch is moved to open position should not be varied by adjusting the operating differential of the switch. Therefore the side 40 of the slot 41 is so shaped that as the arm 37 is rotated in a clockwise direction as seen in Figure 2 the mercury switch 28 will be moved to open circuit position at the same temperature value regardless of the position of the projection 33 longitudinally of the slot 38. In order to accomplish this the side 40 is in the shape of an arc having the center of the shaft 18 as its center when the mercury switch carrier is in its vertical position and the mercury switch in its 50 break position. Therefore when the parts are in

the position where the mercury switch 28 is just about to be opened a rotation of the lever 17 will not produce any rotation of the crank arm 32. The side 41 of the slot 38 is so shaped that the amount of lost motion progressively increases as the lever 17 is rotated from engagement with the stop 23 into engagement with the stop 22.

It will be noted that the differential adjusting mechanism of this device is pivotally mounted to a fixed plate 14 and therefore no strain can be placed on the bimetallic thermostat or on the operating member by a careless manipulation of the differential adjusting lever 17.

This control device has been described as being operated by means of a coiled bimetallic thermostat. It will readily be appreciated however that any type of condition sensitive element capable of rotating the operating rod 13 may be substituted without the use of invention.

As certain changes and modifications in this device may occur to those who are skilled in the art I wish it to be understood that I intend to be limited only by the scope of the appended claims and not by the specific embodiment disclosed.

I claim as my invention:

1. In combination, a switch operable between open and closed positions, a first arm for operating said switch, a sensitive condition responsive element, a second arm connected to said element for rotation thereby upon variations in said condition, one of said arms having an opening of varying width therein and the other of said arms carrying a projection entering said opening to form a lost motion connection, said element causing transverse motion of said projection in said opening to provide a differential between the values of said condition which cause actuation of said switch in opposite directions, a fixed support, means mounted on said fixed support for bodily shifting said first arm and said switch to cause motion of said projection lengthwise of said opening and thereby vary said differential, and a pivotal connection between said first arm and said shifting means for permitting free transverse movement of said projection in said opening, thereby preventing transmission of torque from said shifting means to said sensitive element.

2. In combination, a switch operable between open and closed positions, a first arm for operating said switch, a sensitive condition responsive element, a second arm connected to said element for rotation thereby upon variations in said condition, one of said arms having an opening of varying width therein and the other of said arms carrying a projection entering said opening to form a lost motion connection, said element causing transverse motion of said projection in said opening to provide a differential between the values of said condition which cause actuation of said switch in opposite directions, a fixed support, 50 a lever mounted on said support through a slip friction pivot for supporting said first arm and said switch, and means for rotating said lever about said pivot to cause motion of said projection lengthwise of said opening and thereby vary said differential.

3. In combination, a switch operable between open and closed positions, a first arm for operating said switch, a sensitive condition responsive element, a second arm connected to said element for rotation thereby upon variations in said condition, one of said arms having an opening of varying width therein and the other of said arms carrying a projection entering said opening to form a lost motion connection, said element caus-

ing transverse motion of said projection in said opening to provide a differential between the values of said condition which cause actuation of said switch in opposite directions, a fixed support, mean mounted on said fixed support for bodily shifting said first arm and said switch to cause motion of said projection lengthwise of said opening and thereby vary said differential, means for yieldably restraining said shifting means, and a connection between said first arm and said shifting means for permitting free transverse movement of said projection in said opening, thereby preventing transmission of torque from said shifting means to said sensitive element.

4. In a device of the character described, a fixed support, a differential adjusting member pivotally mounted on said support, a mercury switch carrier pivoted on said member, a mercury switch mounted on said carrier, an arm adapted to be rotated in response to the variations in the value of a variable condition, a lost motion connection between said arm and carrier comprising a tapered slot in said arm and a projection on said carrier extending within said slot, and means for rotating said member whereby the amount of lost motion and hence the differential of operation of said switch is varied.

5. In a device of the character described, a fixed support, a differential adjusting member pivotally mounted on said support, a mercury switch carrier pivoted on said member, a mer-

cury switch mounted on said carrier, an arm adapted to be rotated in response to the variations in the value of a variable condition, a lost motion connection between said arm and carrier comprising a tapered slot in said arm and a projection on said carrier extending within said slot, and means for rotating said member whereby the amount of lost motion and hence the differential of operation of said switch is varied, said tapered slot being so shaped that the adjustment of said member will not affect the condition value at which said switch is actuated in one direction.

6. In a device of the character described, a fixed support, a differential adjusting member pivotally mounted on said support, a mercury switch carrier pivoted on said member, a mercury switch mounted on said carrier, an arm adapted to be rotated in response to the variations in the value of a variable condition, a lost motion connection between said arm and carrier comprising a tapered slot in said arm and a projection on said carrier extending within said slot, means for rotating said member whereby the amount of lost motion and hence the differential of operation of said switch is varied, stops on said fixed support to limit the amount of rotary movement of which said member is capable, and means for indicating the relative position of said member and hence the differential of operation of said switch.
